UNITED STATES PATENT OFFICE

CLYDE C. CAPSHAW, OF DALLAS, TEXAS

PAPER BOX

Application filed March 24, 1931. Serial No. 524,972.

This invention relates to improvements in paper boxes and has for its primary object to provide, in a manner as hereinafter set forth, a paper box of the foldable type which is reinforced at its sides and ends in such a manner that the strength and durability of boxes of that type may be materially increased coincidentally with a reduction in the weight and quality of the material employed, thereby producing a superior box at a minimum cost.

A further object of the invention is to provide a box of the character aforesaid consisting of a pair of foldable sections, each of which may be opened to box forming position by a single movement of the operator or user, and likewise may have the parts thereof returned to their folded positions by a similar movement of the operator, the parts of each of said sections being automatically retained in box forming position when moved thereto.

With the foregoing and other objects in view, the invention consists of the novel construction, combination and arrangement of parts as hereinafter more particularly described, and shown in the accompanying drawings, but it is to be understood that the description and drawings are to be considered as illustrative rather than limitative.

In the accompanying drawings in which like numerals are employed to designate like parts throughout the several views:—

Figure 1 is a perspective view of a box in accordance with this invention.

Figure 2 is an enlarged section taken on the line 2—2 of Figure 1.

Figure 3 is an enlarged section taken on the line 3—3 of Figure 1.

Figure 4 is an enlarged sectional perspective of one of the box sections.

Figure 5 is an enlarged plan of the box section in flat position.

Figure 6 is an enlarged fragmentary plan of the blank from which the section is formed.

Figure 7 is a plan of one of the separable reinforcing members employed at the ends of the section.

Referring to the drawings in detail, the

numerals 1 and 2 respectively indicate generally the upper and lower sections of my improved box. Only the section 2 will be specifically described, as the sections are of identical construction except that they vary in size sufficiently to permit the section 2 to be telescoped within the section 1 when the latter is inverted.

The blank from which the section 2 is formed is shown in Figure 6 and includes a central body portion 3, the area of which represents the area of the box. Formed integrally with the side edges of the body portion 3 are a pair of side extensions 4, and formed integrally with the outer side edges of the extensions 4 are a similar pair of extensions 5. Formed integrally with the end edges of the body portion 3 are a pair of end extensions 6 having a pair of flaps 7 formed integrally with the outer side edges thereof. The lines of joinder between the flaps 7 and extensions 6, extensions 6 and body portion 3, extensions 4 and body portion 3, and extensions 4 and 5 at each side of the body portion, are scored as indicated at 8 in order that the extensions and flaps may be readily folded at such lines of joinder.

At each corner of the body portion 3 is a web 9 which is in the form of a square corresponding in width to the adjacent extensions 4 and 6, and which is formed integrally with the end edges of the latter. Each of the webs 9 is scored at its lines of joinder with the extensions 4 and 6 as indicated at 10. Each web 9 is further scored by means of a row of perforations 11 extending diagonally from the adjacent corner of the body portion 3 and bisecting the web 9.

Formed integrally with each end edge of each extension 5 is a tab 12 which is of less width than the adjacent extension 5 and of greater length than the adjacent web 9. At its line of joinder with the adjacent extension 5, each of the tabs 12 is scored as indicated at 13. Each tab 12 is further scored diagonally as indicated at 14, the score 14 being in registry with the adjacent score 11 when the adjacent extensions 4 and 5 are folded with respect to each other.

The various parts of the blank shown in Figure 6 are folded with respect to each other to form, in connection with a pair of separable reinforcing members 15, a flat 5 box section as shown in Figure 5. When so forming the section, the members 15 are seated on the end extensions 6 with the latter extended in continuation of the body portion 3. The extensions 5 are folded onto 10 the sections 4, after which the latter are folded to position the extensions 5 on side marginal portions of the body portion 3, in which position the tabs 12 extend across the reinforcing members 15 and flaps 7, and 15 the webs 9 are seated on the tabs 12 with the scores 11 in registry with the scores 14. The outer end portions 16 of the tabs 12 are then folded under along the score lines 14 to extend such portions 16 longitudinally 20 of the reinforcing members 15. The flaps 7 then are folded inwardly over the webs 9 and the end portions 16 of the tabs 12. The various parts then are secured in their relative positions by a pair of staples or the 25 like 17 at each end of the section, each staple extending through a flap 7, end portion 16, reinforcing member 15, and end extension 6. With the parts of the section arranged as aforesaid, all of such parts lie 30 flat whereby a number of the sections may be stacked in a minimum of space for storing or shipping.

When it is desired to assemble one of the lower sections 2 with respect to a section 35 1 to form a box, the extensions 4, carrying the extensions 5 therewith, are swung outwardly to extend at right angles to the body portion 3. This movement of the extensions 4 causes the webs 9 to be folded 40 along their scores 11 whereby the portions 18 of the webs 9 operate as wedges beneath the flaps 7 to swing the extensions 6 inwardly into positions at right angles to the body portion 3. This movement further 45 causes the inner portions 19 of the tabs 12 to straighten out in continuation of the outer portion 16, in which position they are automatically locked by the flaps 7. The section, with the parts thereof arranged as 50 aforesaid, forms one half of a box for assembly with respect to the corresponding half of the box formed in the same manner. If it is desired to return the parts of the section to their original positions, this may be accomplished simply by grasping 55 the end extensions 6, centrally thereof, and swinging the same outwardly. This movement of the extensions 6 causes the flaps 7 to release the tabs 12 and further causes the inner portions 19 thereof to return to their folded positions, while the folded portions 18 of the webs 9 return to their extended positions.

Upon reference to Figure 3, it will be 60 observed that the side walls of each section

of the box are of double thickness with the double side walls of one section telescoped within the double side walls of the other section. Upon reference to Figure 2, it will be observed that the end walls of each section are of double thickness throughout their entire areas with the double end walls of one section telescoped within the double end walls of the other section. The end walls are further reinforced by the flaps 7, tabs 75 12, and folded webs 9, adjacent the corners of the box.

It will be apparent that it is but the work of a moment to open one of the sections to box forming position, as the only operation necessary to be performed by the operator is to grasp the side extensions 4 and swing them outwardly with respect to the body portion 3. Likewise it is but the work of a moment to return the parts of the section 85 to their folded positions, as the only operation necessary to be performed by the operator is to swing the end extensions 6 outwardly with respect to the body portion 3.

It is thought that the many advantages 90 of paper boxes in accordance with this invention will be readily apparent, and although the preferred embodiment of the invention is as illustrated and described, it is to be understood that changes in the size, shape and arrangement of parts may be resorted to, so long as such changes fall within the scope of the invention as defined in the appended claim:

What I claim is:—

An extendible box section comprising, a body part, a pair of shiftable end wall forming members hinged to the ends of said body part and normally forming a lengthwise continuation of the latter, a reinforcing member positioned upon the upper face of and coextensive with each of the end wall forming members, a pair of shiftable side wall forming members hinged to and normally arranged over said body part, an extension normally interposed between each side wall forming member and said body part, said extensions hinged to and coextensive with said side wall forming members, extendible normally diagonally outwardly 115 folded tabs hinged to the ends of said extensions and having the outer folds thereof disposed lengthwise of the upper face of said reinforcing members adjacent the ends of the latter, inwardly diagonally foldable 120 normally extended webs integral with the side and end wall forming members and seated upon a part of the outer folds of said tabs, flaps hinged to the end wall forming members, seated upon said webs and arranged over the remaining part of said outer folds, and means for permanently securing said flaps, outer folds, reinforcing and end wall forming members together to provide in connection with said tabs the coupling of the 125

end and side wall forming members together, each of said webs being foldable inwardly upon itself on shifting the side wall forming members to a position at right angles to said body part whereby the tabs will be extended and the end wall forming members disposed in a position at right angles to said body part and side wall forming members.

5 10 In testimony whereof, I affix my signature hereto.

CLYDE C. CAPSHAW.
